GEOMETRICAL INSTRUMENT

Leland H. Isaacson, Washington, D. C.

Application November 27, 1942, Serial No. 467,110

4 Claims. (Cl. 33—148)

(Granted under the act of March 3, 1883, as amended April 30, 1928; 370 O. G. 757)

This application is made under the act of March 3, 1883, as amended by the act of April 30, 1928, and the invention herein described, if patented, may be manufactured and used by or for the Government of the United States of America for governmental purposes without the payment to me of any royalty thereon.

My invention relates to geometrical instruments.

An object of my invention is to provide an instrument which will rapidly and accurately measure distances between selected points on aerial photographs.

A further object is to afford generally an accurate means of measuring distances between points and of establishing points a given distance apart.

Other objects will appear from the following description.

In the accompanying drawings, forming a part of this specification,

Figure 1 is a plan view of a preferred embodiment of my invention;

Figure 2 is a side elevation of the same embodiment;

Figure 3 is a vertical section on the line 3—3 of Figure 1;

Figure 4 is a plan view of the vernier magnifier assembly 34, showing the method of attachment to the lever 7; and

Figure 5 is a side elevation of the same.

Similar numerals refer to similar parts throughout the several views.

The embodiment illustrated in the drawings comprises a base 6 and a lever 7. The base 6 is supported by three legs 8, held in place with countersunk screws 9, and by a pivot leg 10 having a roller 11 at its lower end to provide rolling contact at this point of support. The pivot leg 10 is fixed in the base 6 by a press or shrink fit in the boss 12, and extends upwardly through the base 6 to also act as a pivot for the lever 7. A nut 13, tapped to allow free movement of the lever 7, engages screw threads on the upper end of the pivot leg 10.

Needle-point assemblies which are designated in the drawing by the numerals 14 and 15 are mounted on both the base 6 and the lever 7 by press or shrink fits through bosses 16. Figure 3 shows a vertical section of the base needle-point assembly 14, which consists of a central shaft 17, provided with a needle-point 18 at the lower end and extending upward through a sleeve 19 to engage tapped threads in a cap 20 having a tubular

portion 21 extending downward and also received by the sleeve 19. A tension spring 22, disposed around the central shaft 17, and anchored to the sleeve 19 and the cap 20, exerts a force to hold the needle-point 18 yieldingly in a downward position. Means to restrain the tension spring 22 is provided by an inverted L-slot 23 in the sleeve 19 and a small screw 24 which passes through the L-slot 23 and engages the tubular portion 21 of the cap 20. By raising the cap 20 and turning it counter-clockwise, the head of the screw 24 can be placed in the horizontal portion of the L-slot 23, thus holding the needle-point 18 in an upward position against the force of the tension spring 22. The lever needle-point assembly 15 is similar in construction, except that the tension spring 22 is replaced by a compression spring 25 disposed around the central shaft 26 and acting against the sleeve 27 and the cap 28 to hold the needle-point 29 yieldingly in an upward position; and instead of the L-slot 23, a vertical slot 30 is used, which, together with the screw 31 held in the tubular portion 32 of the cap 28, limits the action of the compression spring 25, but allows the needle-point 29 to be pressed downward.

A scale 33 is arranged on both faces of the V-shaped arc portion of the base 6 in such a manner that a reading indicated by the lever 7 will be a measure of the distance between the needle-points 18 and 29. The scale 33 can be delineated directly on the base 6, or it can be placed on a suitable backing and mounted on the base 6. The arrangement of the scale 33 on both faces of the arc portion of the base 6 allows reading to be taken from two directions, so that the instrument can be operated by one person alone, or one person can record readings while another sets the instrument. As illustrated in the drawing, calibrations on the scale 33 begin at one inch and extend to seven inches, a scale marking being provided for each interval of one-hundredth of an inch. Inches, tenths of an inch and five-hundredths of an inch are distinguished by a difference in length of the corresponding scale marking, and inches are designated by a numeral and tenths of an inch are marked "10," "20," "30," and so forth. The calibration and range of the scale 33 can, of course, be otherwise arranged for adaptation to particular purposes.

To obtain readings on the scale 33, a vernier magnifier assembly 34 is attached to the underside of the lever 7 by countersunk screws 35. The vernier magnifier assembly 34 is composed of two magnifying lenses 36, having hair-line indicators, and a frame 37. The frame 37 carries the lenses

36, and is shaped to the V-form of the arc portion of the base 6, so that each lens 36 is in a position to give readings on a respective face of the scale 33.

The embodiment of my invention set forth above is particularly adapted for use with aerial photographs, where it is desired to measure distances from a center point to a number of selected points in the outer area of the photograph. To accomplish this result, the photograph is placed under the roller 11 of the pivot leg 10 in such a position that the center point will coincide with the needle-point 18 when it is released to its full downward position. The roller 11 will allow the photograph to be rotated around the needle-point 18, so that the photograph and the lever 7 can then be adjusted to bring the needle-point 29 in line with any one of the selected points in the outer area. When needle-point 29 is depressed to coincide with a selected point, the distance between that point and the center point of the photograph is the same as between the needle-points 18 and 29, and a reading on the scale 33 is a measure of that distance. The needle-point 29 is then allowed to assume its upward position, and the procedure is repeated to bring a second point into line, and so on. When the measuring has been completed, the needle-point 18 is locked in its upward position, allowing the photograph to be removed.

Use of my invention has provided a considerable saving of time in measuring aerial photographs. It is not, however, restricted to such use, but may be adapted generally to the measurement of distance.

Having thus described my invention, I claim:

1. A measuring instrument comprising a base, means for supporting said base on a plane surface, a pointed element attached to said base, means for vertically moving the pointed element relative to said base, yieldable means urging said pointed element downward to contact the plane surface, means for holding said pointed element out of contact with the plane surface against the action of said yieldable means, a lever pivoted on said base, a pointed element attached to said lever, and a circular scale on said base adjacent to said lever, the radial center of said scale being coincident with the pivot of said lever.

2. A measuring instrument comprising a base,

means for supporting said base on a plane surface, a pointed element attached to said base, a lever pivoted on said base, a pointed element attached to said lever, means for vertically moving said last-mentioned pointed element in and out of contact with the plane surface, yieldable means urging said last-mentioned pointed element upward out of contact with the plane surface, and a circular scale on said base adjacent to said lever, the radial center of said scale being coincident with the pivot of said lever.

3. A measuring instrument comprising a base, means for supporting said base on a plane surface, a pointed element attached to said base, a lever pivoted on said base, said supporting means including a post adjacent to the pivot of said lever and a roller on said post to contact the plane surface, a pointed element attached to said lever, and a circular scale on said base adjacent to said lever, the radial center of said scale being coincident with the pivot of said lever.

4. A measuring instrument comprising a base, means for supporting said base on a plane surface, a pointed element attached to said base, a lever pivoted on said base, said supporting means including a post adjacent to the pivot of said lever and a roller on said post to contact the plane surface, a pointed element attached to said lever, means for vertically moving the pointed element relative to said base, yieldable means urging said pointed element downward to contact the plane surface, means for holding said pointed element out of contact with the plane surface against the action of said yieldable means, a lever pivoted on said base, said supporting means including a post adjacent to the pivot of said lever and a roller on said post to contact the plane surface, a pointed element attached to said lever, means for vertically moving said last-mentioned pointed element in and out of contact with the plane surface, yieldable means urging said last-mentioned pointed element upward out of contact with the plane surface, a circular scale on said base adjacent to said lever, the radial center of said scale being coincident with the pivot of said lever, said scale being calibrated in accordance with the ratio of movement between that part of said lever to which it is adjacent and said last-mentioned pointed element, and an indicator attached to said lever adjacent to said scale, whereby the position of the adjacent portion of said lever with respect to said scale is defined.
